UNITED STATES PATENT OFFICE.

GEORGE W. FURROW, OF TROY, OHIO.

HOOD FOR EMERY-WHEELS.

956,762.

Specification of Letters Patent. Patented May 3, 1910.

Application filed February 21, 1910. Serial No. 545,079.

To all whom it may concern:

Be it known that I, GEORGE W. FURROW, a citizen of the United States, residing at Troy, in the county of Miami and State of Ohio, have invented certain new and useful Improvements in Hoods for Emery-Wheels, of which the following is a specification.

My invention relates to improvements in hoods for grinding, polishing and buffing 10 wheels.

The object of my invention is to provide a hood which will be particularly effective in carrying away the dirt and dust incident to devices of this character, the invention 15 being more particularly adapted for removing dust from above the work and also those particles which adhere to and are carried around by the wheel and are thrown off at a point where the work is applied.

20 The invention consists in the constructions and combinations of parts hereinafter described and set forth in the claims.

In the drawings: Figure 1 is a side elevation of the device embodying my invention. 25 Fig. 2 is a vertical section on the line $x-x$ of Fig. 3. Fig. 3 is a front view of the same. Fig. 4 is a top plan view of the hinged forward portion of the conduit hereinafter referred to. Fig. 5 is a section of the same 30 on the line $y-y$ of Fig. 4.

Like parts are represented by similar characters of reference in the several views.

In the said drawings, a and a^1 represent the hood of my improved device, preferably 35 formed in two parts hinged together at a^2 in the usual manner.

a^3 represents a grinding, polishing or buffing wheel mounted upon one end of the shaft a^4 which is supported in suitable bearings on the standard a^5 . The hood or casing extends about the wheel except for the open portion at the forward end and has attached at its rear end a conduit a^6 which may be connected to any suitable form of suction 40 fan in the usual way.

50 Located in the upper and rear portions of the hood is a division wall b which extends from side to side of the hood so as to form a conduit b^1 which communicates with the conduit a^6 the conduit b^1 beginning at the forward part of the hood immediately above the work and being adapted to receive the dust and dirt, which will be carried rearwardly through the same into the main conduit a^6 .

55 It has been common in devices of this kind

to leave an open space between the wheel and the upper part of the hood and it has been attempted to remove some of the dirt and dust by that route as well as through a 60 suitable conduit or passageway formed below the wheel, but it has been found that the current of air generated by the revolution of the wheel materially interferes with the proper removal of the dust above the 65 wheel. By my construction in which I employ a conduit above the wheel which is entirely separate and removed from the wheel, the proper carrying away of the dust above the work will not be interfered with 70 by the current of air created by the revolution of the wheel.

To compensate for the wear on the wheel and also for different sized wheels, I have the forward part of the division wall, b , in 75 the nature of a hinged portion, c , pivotally supported at c^1 to the forward part of the division wall proper. A thumb-screw c^2 extends through the slotted opening c^3 in a side of the hood and engaging an ear or lug 80 c^4 on the hinged portion, furnishes the means for holding this hinged portion in any position of adjustment with respect to the wheel. I also slidably mount in suitable guides d^1 on said hinged portion a sliding shield d , which may be held in any position of adjustment with respect to said hinged portion c by the said screw c^2 . This shield, d , may be slid down to any position 85 desired with respect to the wheel and prevent the small particles which adhere to the wheel from flying up into the face of the operator.

Having thus described my invention, I claim:

1. In a device of the character described, a wheel, a hood, for said wheel formed with a work opening at the forward portion thereof, and a conduit in said hood closed to the wheel and extending upwardly over 100 said wheel, substantially as specified.

2. In a device of the character described, a wheel, a hood for said wheel formed with a work opening at its forward portion, and a conduit in said hood closed to the wheel 105 and extending upwardly over said wheel, said conduit beginning at a point coincident with said work opening, substantially as specified.

3. In a device of the character described, a wheel, a hood for said wheel formed with a work opening at the forward portion 110

thereof, a conduit in said hood closed to the wheel and extending upwardly over said wheel, and an adjustable hinged portion at the forward end of said conduit, substantially as specified.

4. In a device of the character described, a wheel, a hood for said wheel, and a conduit formed in said hood, extending upwardly over said wheel, said conduit having an adjustable hinged portion at the for-

ward end thereof, and an adjustable shield carried by said hinged portion, substantially as specified.

In testimony whereof, I have hereunto set my hand this 10th day of February, 1910. 15

GEORGE W. FURROW.
